UNITED STATES PATENT OFFICE.

WILLIAM FAY, OF ST. LOUIS, MISSOURI.

EXTENSION-TABLE.

SPECIFICATION forming part of Letters Patent No. 224,007, dated February 3, 1880.

Application filed April 4, 1879.

To all whom it may concern:

Be it known that I, WILLIAM FAY, of the city of St. Louis, Missouri, have made a new and useful Improvement in Extension-Tables, 5 of which the following is a full, clear, and exact description, reference being had to the annexed drawings, making a part of this specification, in which—

Figure 1 is a view, in perspective, of a table 10 having the improvements, the table being opened out and the leaves being removed. The dotted lines indicate the position of the extension-strips just before being drawn out in straight lines. Fig. 2 is a plan of the table 15 as opened out in a curve, the leaves being removed; Fig. 3, a plan of the table as opened out partly in a straight direction and partly in a curved direction; Fig. 4, a plan of the table extended in a straight direction, the top being 20 formed with tapered leaves; and Figs. 5 and 6, details in perspective, being, respectively, a view showing the latch holding the end extension-strip at the proper angle when the table is extended in a curve and a view showing 25 the manner of attaching one of the tie-rods to an extension-strip.

The same letters denote the same parts.

The present invention is an improvement in extension-tables having the ends connected 30 by folding strips.

Referring to the drawings, A, Fig. 1, represents a table having the improved extension-strips. B B' represent the two ends of the table, and which, except as modified by the present improvement, may be of the usual 35 construction.

C C' represent the strips used in extending the table and connecting the ends B B'. Instead of sliding upon each other in the manner termed "telescoping," the strips, by means 40 of the hinges c c', are hinged to each other and to the ends B B', as shown in Figs. 1, 2, and 3. A portion, c, of the hinges is arranged for every other pair of strips to fold outwardly, and the other portion, c', for the alternate 45 pairs of strips to fold inwardly. The strips are also provided, as a partial support, with legs c² c².

When the ends B B' are closed together 50 the strips fold upon each other, and when

thus folded they occupy the space a beneath the tops a' a' of the ends B B'.

If desired, a portion of the space a may be taken for a drawer, D, for, by reason of the compactness of the strips when folded, there 55 is ample room afforded for a drawer.

As the ends B B' are drawn apart the strips C C' unfold.

If it is desired to have a straight table, the strips are drawn out straight and evenly on 60 both sides of the table, as shown in Fig. 1. The top of the table is then completed by means of the leaves E E, which are laid upon the strips.

By means of the strips C C' the table can 65 also be extended in a curved direction, (shown in Fig. 2,) in which case the outer line, C, of the strips will be drawn out more than the inner line, C'.

The strips are held in place in the following manner: Rods F F' F' F', having ends f f' suitably shaped to engage in perforations f' in the strips, as indicated in Fig. 6, extend from one line of strips to the other line, serving to tie the lines together. The rods cross 75 each other, their preferable arrangement and connection with the strips being that shown in Fig. 2—that is, the rods are arranged in pairs, F F, F' F', F² F², each pair being connected at both ends to an inwardly-folding 80 pair of strips. The leaves G G in this case are made tapering, and are arranged as indicated by the dotted lines of Fig. 2, and they are fastened together by means of clips.

The tapering leaves G G can, by arranging 85 them as in Fig. 4, be used to form a straight table.

The extension of the table can be further modified, as shown in Fig. 3—that is, the table can be extended partly in a straight direction and partly in a curve, in which case the strips C C' in the straight part H are extended as in Fig. 1, and in the curved part I as in Fig. 2. Straight leaves F F can be used upon the straight part H, and tapering leaves 95 G are used upon the part I.

When any part of the table is extended in a curved form, it is desirable, for the purpose of more firmly holding the strips in place, to employ the device shown more distinctly in 100

Fig. 5. The end strip, C², is provided with a latch, c², the free end of which, after the strip is turned to the proper angle, is made to engage in a groove, c³, in the end B', and there-
5 by hold the strip firmly.

I am aware that extension-tables having folding strips for connecting the ends of the table have heretofore been used.

I claim—

- 10 1. The combination of the ends B B', strips C C', tie-rods F F', leaves G G, the strip C²,

having the latch c², and the end B', having the groove c³, substantially as described.

2. The combination of the end B, strips C C', tie-rods F F', strip C², having the latch c², and the end B', having the groove c³, for the purpose described.

WILLIAM FAY.
